Application November 8, 1950, Serial No. 194,700

8 Claims. (Cl. 299—35)

(Granted under Title 35, U. S. Code (1952),
sec. 266)

1

This invention relates to fluid dispensing apparatus, particularly intended for use with aerosol mixtures containing many types of active ingredients. The apparatus is well suited for use in connection with stationary as well as mobile installations, and has already been eminently satisfactory in the so-called disinfection of aircraft.

The fluid dispensing apparatus contemplated herein comprises an aerosol supply reservoir, an aerosol dispensing unit remote from the reservoir, conduit means connecting the unit with the reservoir, the dispensing unit including a storage vessel, a discharge nozzle, and a valve interposed between the vessel and nozzle, and means remote from the unit for actuating the valve. The supply reservoir is preferably located in a relatively warm environment, while the aerosol dispensing unit remote therefrom is preferably located in an environment cooler than that in which the reservoir is located. The valve interposed between the vessel and nozzle is preferably electromagnetically actuated for many applications of the invention, in which cases, the remote actuating means may assume the form of electrical switching apparatus. More specifically, such remote actuating means may be automatic time controlled cycling means for opening and closing the valve. In a great many of the installations contemplated for the present invention, there will be a plurality of such aerosol dispensing units and the remote actuating means will ordinarily operate the valves of these units in unison. A valved coupling is preferably carried by the conduit means for closing it upon disconnection of the unit therefrom to avoid the escape of any appreciable quantity of the contained fluid. A quickly detachable coupling is also preferably carried by the conduit means and unit, the actuating means remote from the unit communicating with the unit through the coupling for actuating the valve.

The apparatus preferably comprises an aerosol supply conduit, a dispensing unit separably connected with the conduit, the unit including a storage vessel, a discharge nozzle, and the unit having fluid passages for establishing communication between the conduit, vessel and nozzle, and a quickly attachable and detachable fluid coupling separably connecting the conduit and unit. A valve is preferably interposed between the conduit and nozzle for controlling discharge from the nozzle, and such valve is preferably electromagnetically actuated from a remote position. In addition to separably connecting the

2

fluid supply conduit with the unit, the coupling also preferably establishes an electrical connection between a source of current and an actuating solenoid carried by the unit for operating a valve used to establish communication between the vessel and nozzle. The preferred form of the unit here under consideration contains a plurality of valves serially disposed between the conduit and nozzle, and in the interest of simplicity and compactness, a common spring is used to bias two of these valves towards their closed positions, one of the valves being that which is electromagnetically controlled, and the other being a check valve. The storage vessel is preferably composed of a thermally conductive and paramagnetic material, and as compared with its volume, has a large surface area for effective cooling of the aerosol mixture which it contains. The electromagnetic valve arrangement utilizes an armature in the unit controlling a port between the vessel and nozzle, an electrical winding for energizing the armature, and a tapered end on the armature to provide a large surface in the magnetic circuit. The electromagnetically actuated valve is preferably of the reciprocatory type and contains one or more longitudinal passages for the flow of fluid. The valve body is preferably annular, receiving a disc in one of its ends for cooperation with a seat, one surface of the disc engaging the seat and the opposed surface being in continuous communication with the vessel.

A more complete understanding of the invention will follow from a description of the drawings wherein:

Fig. 1 is a somewhat diagrammatic representation of a system embodying the invention;

Fig. 2 is a sectional elevation taken along line 2—2 of Fig. 1;

Fig. 3 is a section taken along line 3—3 of Fig. 2;

Fig. 4 is a section taken along line 4—4 of Fig. 2; and

Fig. 5 is a section taken along line 5—5 of Fig. 2.

The apparatus depicted in the drawings includes a supply reservoir 10 for the aerosol mixtures to be dispensed, a control valve 12 for establishing communication between the supply reservoir and the remote dispensing units 14 through suitable conduits 16 containing a solenoid valve 18, a filter 20, a manual shut-off valve 22, and as depicted in Fig. 1, interconnecting the several dispensing units themselves.

Electrical switching apparatus 24, connected to

supply leads 26 through a main switch 28, serves to remotely control the solenoid valve 18 through a conductor 30, and actuates the dispensing units 14 through an electrical conductor 32. Inasmuch as one side of the electrical system is shown as connected to ground 34 adjacent the switch 28, one side of the winding of the solenoid valve 18 is also connected to ground as are the windings of the individual dispensing units.

The supply reservoir is maintained in a warm environment or area, diagrammatically represented in Fig. 1 as being to the left of the broken line 36. The dispensing units themselves, shown to the right of this broken line, are maintained in a relatively cool environment or area, in order that the temperature differential will be sufficient to maintain a fluid flow throughout the conduits from the supply reservoir to the dispensing units by means of the pressure within the supply reservoir without the use of supplemental pumping apparatus in the conduits. This temperature differential is the preferred means of preventing vaporization within the conduits, since it eliminates the need for compression pumps which would add to the weight and complexity of systems constructed according to the instant invention.

Each of the dispensing units 14 comprises a storage vessel 38 and a discharge expansion nozzle 40 whose characteristics promote additional cooling in the area occupied by the dispensing units.

Each of the nozzles 40 contains a plurality of laterally disposed small bores 42, a filter 44 being carried within each nozzle adjacent the discharge ports. As depicted in Fig. 2, the nozzle is secured to the nose piece 46 of the dispensing unit by the clamping action of an internally threaded sleeve 48. The nose piece is provided with an internal bore 50 which establishes communication between the source of fluid and the chamber 52 within the nozzle itself. The other end of the bore 50 terminates in a relatively sharp annular lip 54 defining a valve seat. Externally, the nose piece 46 carries a flange 56 serving as an abutment for a deformable gasket 58 having another surface engaged by the end of an internally threaded hub 60 to which one portion of the storage vessel 38 is secured by means of a weld 64. The hub 60 is provided with a plurality of radial openings 66 to establish communication between the storage vessel 38 and the internal bore 50 of the nose piece, at such times as the valve seat 54 is uncovered. The opposite end of the storage vessel 38 is connected by a weld 68 to a flange 70 formed on the main body member 72. It will be evident from Fig. 2 that the storage vessel 38 assumes the form of a thin walled shell having a bell member 74 receiving a spigot member 76 secured together by an annular weld 78. A portion of the main body member projecting forwardly from the flange 70 defines a pole piece 80 whose end is inclined with respect to a radius of the body member, so as to provide a relatively large pole tip for cooperation with an armature 82 having an end 84 complementary to the pole face 80, and another and containing a counterbore 86 to receive a valve disc 88 for cooperation with the valve seat 54. Thus it will follow that the armature 82 also serves as a valve body. The member 82 is provided with an internal bore 90 to maintain communication between the rear surface of the valve disc 88 and the storage vessel 38, to avoid any tendency which might other-

wise occur to force the disc from its counterbore. Communication between the storage vessel and the valve body 82 is maintained through inclined passages 92 extending from the internal bore 94 of the main body member to an intermediate portion of the storage vessel. The valve body or armature 82 contains a plurality of longitudinal grooves 96 through which fluid can flow freely to avoid any pumping action as result of reciprocatory movements of the valve body or armature 82.

The main body member 72 and the hub 60 are bridged by a non-magnetic sleeve 98 which serves as a spool for an electromagnetic winding 100 located within the storage vessel 38 between the hub 60 and main body member 72. The hub 60, main body member 72 and the halves of the shell defining the storage vessel 38 are composed of paramagnetic material to serve as a part of the flux path within which the armature-valve body 82 operates.

The internal bore of the main body member 72 is provided with a thread 102 for the reception of a check valve 104 of the well known type used in the tubes of pneumatic tires, the spring 106 of this valve serving its usual function, and in addition, having a bearing upon a portion of the armature 82 and biasing it towards its closed position with its disc 88 in engagement with its seat 54. In this device check valve 104 is operative to permit the flow of fluid under pressure into the storage vessel 38 and effective in its normally closed position to prevent the flow of fluid out of the storage vessel 38 through the internal bore and out the open end of main body member 72. Consequently, fluid contained in the storage vessel 38 will not be released and lost when the dispensing unit 14 is disconnected from the conduit.

The flange 70 of the main body member 72 is penetrated by a plurality of openings 108, each of which receives a bushing 110 through which a screw 112 is passed in fluid tight relationship with the flange, the bushing being composed of a suitable packing composition. The threaded end of the screw 112 receives a fiber washer or the like 114 and a nut 116. The head 118 of the screw bears upon a recessed portion of a conducting ring 120, between which and the flange 70, a body of insulating material 122 is interposed. The ring 120 has a longitudinally extending portion 124 which serves to establish electrical communication between the winding 100 and a source of current, and serves the further function of actuating a quickly attachable and detachable coupling 126 by the mere insertion of the main body member into a suitable socket. For purposes of this coupling operation, the main body member is provided with an annular groove 128 having inclined walls 130 for cooperation with a suitable number of balls 132 carried by radial pockets 134 of the socket member 136. The socket member 136 is provided with an internal bore 138 for reception of the grooved end of the main body member 72, the internal bore 138 terminating at a shoulder 140 against which a toroidal or other suitable deformable sealing member 142 is deformed by the tapered end portion 144 of the body member 72. Within the body member 72, near its open end, a spider 146 is threadedly received for cooperation with the stem 148 of a plunger operated disconnect valve 150 carried within the socket member 136. The passage controlled by this disconnect valve 150, is

depicted in Fig. 2 as communicating with a passage 152 at right angles thereto. It will be noted that the valve 150 is another familiar type employed commonly in connection with pneumatic tubes for automobile tires, which has a biasing spring inside. In this device the disconnect valve 150 is effective in its closed position to seal the passage 152 in the conduit against the loss of fluid when the dispensing unit 14 is disconnected from the conduit, and operative when the stem 148 is deflected by the spider 146 to permit the flow of fluid into the dispensing unit from the conduit.

The socket member 136 provides an outer cylindrical surface 154 covered by an annular sleeve 156 of electrical insulating material, and an annular washer 158 of similar insulating material is interposed between a shoulder 160 formed on the socket member and a conducting ring 162 surrounding the sleeve 156 and having a plurality of longitudinally extending fingers 164 serving as abutments for a conducting spring 166 and serving the further function of guiding a non-conducting sleeve 168 composed of a suitable plastic composition or the like. At the open end of the socket member 136, the insulating sleeve 156 is grooved to receive a retaining ring 170 to prevent loss of an actuating ring 172 when the dispensing unit is removed from the socket 136. The actuating ring 172 engages the end of the spring 166 remote from the conducting fingers 164, as result of which, the actuating ring 172 is biased towards the left as viewed in Fig. 2.

The actuating ring 172 is also retained within the sleeve 168 by means of a retaining ring 171 and urged into contact with this retaining ring by means of a spring 174 whose other end bears upon a portion of the sleeve 168 defined by a counterbore 176. The sleeve 168 is formed with an internal cam surface 178 for cooperation with the balls 132, and an annular chamber 180 into which the balls can be moved radially in their retracted positions for removal of the dispensing units, the sleeve also providing a confining surface 182 for maintaining the balls in their latching positions to secure the dispensing unit assembled with the socket member. The conducting ring 162 receives a conducting threaded member 184 carrying a nut 186 and washers 188 for reception of the electrical conductors 32 for actuation of the electromagnetic valves defined by the windings 100 and armatures 82.

As will be clear to those skilled in the art, when the dispensing unit has been withdrawn from the socket member 136, the valve 150 will close to prevent the escape of any of the fluid in the line 16, and the actuating ring 172 will be urged toward the open end of the socket member along with the sleeve 168 under the influence of the springs 166 and 174. With the parts in these positions, when the dispensing unit is inserted into the socket member, the flange 124 will abut the actuating ring 172 tending to move it and its associated sleeve 168 towards the right, the cam surface 178 engaging the balls 132 tending to move them to their confined positions. As soon as the annular groove 128 registers with the balls 132, the sleeve 168 can move towards the right with its confining surface 182 in contact with the balls to effect a positive latching action. When it is desired to uncouple the parts, it is merely necessary to move the sleeve 168 towards the left to release the balls 132 into the chamber 180, under which conditions, the springs 166 and 174 will tend to urge the dispensing unit out-

wardly from the socket member, the dispensing unit being completely removed by the hand of the operator. It will be evident as well that this fluid coupling and uncoupling operation is attended by a similar electrical coupling and uncoupling operation, the current passing from the supply line 26 through the timing apparatus 24, conductors 32, conductive ring 162 and its conductive fingers 164, through the spring 166 and conductive actuating member 172 to the flange 124, through the screws 112 and suitable leads 190 to the winding 100 of the electromagnetic valve. When the winding of this valve is energized, the armature 82 will be retracted to withdraw the valve disc 88 from its seat 54, whereupon fluid within the reservoir 62 will pass through the internal bore 50 of the nose piece 46, through the filter 44 and finally, through the discharge ports 42 of the nozzle 40.

In the interests of economy and efficient operation, the fluid conduits 16 are preferably relatively small, since any break in the system should not result in the loss of any appreciable amount of material. Moreover, since it has been found that intermittent operation in the case of insecticides is preferable to continuous operation, the system can permit the supply within the storage vessels of the dispensing units to be replenished from the supply reservoir between discharge operations. The timing of such operations will be effected by a suitable time controlled switch housed within the apparatus 24, which will also control the solenoid valve 18 at predetermined intervals to completely shut off or open the conduit 16 at the proper times.

Whereas only one specific form of the apparatus has been illustrated for purposes of example in describing this invention, variations will suggest themselves to those skilled in the art, just as they have been realized already by the present inventors, and accordingly, the invention should not be restricted to the apparatus illustrated beyond the scope of the appended claims.

The invention described herein may be manufactured and used by or for the Government of the United States of America for governmental purposes without the payment of any royalties thereon or therefor.

We claim:

1. Fluid dispensing apparatus comprising an aerosol supply reservoir, a plurality of aerosol dispensing units remote from said reservoir, conduit means interconnecting said units with said reservoir, each dispensing unit including a storage vessel, a discharge nozzle and a valve interposed between said vessel and nozzle, and means remote from said units for actuating said valves in unison.

2. Fluid dispensing apparatus comprising an aerosol supply reservoir, an aerosol dispensing unit remote from said reservoir, conduit means interconnecting said unit with said reservoir, a valved coupling carried by said conduit means for closing the same upon disconnection of said unit therefrom, said dispensing unit including a storage vessel, a discharge nozzle and a valve interposed between said vessel and nozzle, and means remote from said unit for actuating said valve.

3. Fluid dispensing apparatus comprising an aerosol supply reservoir, an aerosol dispensing unit remote from said reservoir, conduit means interconnecting said unit with said reservoir, a quickly detachable coupling carried by said

conduit means and unit, said dispensing unit including a storage vessel, a discharge nozzle and a valve interposed between said vessel and nozzle, and means remote from said unit and communicating therewith through said coupling for actuating said valve.

4. Fluid dispensing apparatus comprising an aerosol supply conduit, a current supply conductor, a dispensing unit separably connected with said conduit and conductor; said unit including a storage vessel, a discharge nozzle, and a valve having an actuating solenoid for establishing communication between said vessel and nozzle; and a quickly attachable and detachable coupling separably connecting said conduit with said unit and said conductor with said solenoid.

5. Fluid dispensing apparatus comprising an aerosol supply conduit, a dispensing unit separably connected with said conduit; said unit including a storage vessel, a discharge nozzle, and having fluid passages for establishing communication between said conduit, vessel and nozzle; a plurality of valves serially disposed between said conduit and nozzle, and a common spring biasing two of said valves towards their closed positions.

6. Fluid dispensing apparatus comprising an aerosol supply conduit, a dispensing unit separably connected with said conduit; said unit including a storage vessel, a discharge nozzle, and having fluid passages for establishing communication between said conduit, vessel and nozzle; an armature in said unit controlling a port between said vessel and nozzle, and an electrical winding for energizing said armature, said armature having a tapered end providing a large magnetic surface.

7. Fluid dispensing apparatus comprising an

5 aerosol supply conduit, a dispensing unit separably connected with said conduit; said unit including a storage vessel and a discharge nozzle separably secured to said vessel, said unit having fluid passages for establishing communication between said conduit, vessel and nozzle; and a quickly attachable and detachable fluid coupling separably connecting said conduit and unit, said coupling containing valves biased towards their closed positions to prevent the loss of fluid upon separation of said conduit and unit.
